UNITED STATES PATENT OFFICE.

ARMOND D. HUDSON, OF KEYAPAH, AND EDWARD L. SMITH, OF MILLBORO, SOUTH DAKOTA, ASSIGNORS OF ONE-FOURTH TO WORLEY A. TIBBLES, OF MILLBORO, SOUTH DAKOTA, AND ONE-FOURTH TO BENJAMIN B. BUTTS, OF WINNER, SOUTH DAKOTA.

MECHANICAL MOVEMENT.

Application filed June 23, 1926, Serial No. 118,040. Renewed May 31, 1927.

This invention relates to improvements in mechanical movements, and objects of the invention are to produce a very effective, simple and economical apparatus which may

5 be used as a convenient means for transmitting power, which is adapted to continuously operate for a long period of time without requiring repair, and which is particularly intended for effecting the smooth 10 operation and continuous rotation of a driven shaft.

Other objects will become apparent as the nature of the invention is better understood, and the same consists in the novel form, combination and arrangement of parts herein-after more fully described, shown in the accompanying drawings and claimed.

In the drawings, wherein like reference characters indicate corresponding parts 20 throughout the several views,

Figure 1 is a side elevational view of a power transmitting mechanism constructed in accordance with the present invention;

Figure 2 is a top plan view thereof;

25 Figure 3 is an end elevational view looking toward the right of Figure 1; and

Figure 4 is a substantially central vertical longitudinal sectional view of the device shown in Figure 1.

30 Referring more in detail to the drawings, the form of the invention shown consists of a suitable frame embodying a pair of vertical rigidly connected side frame plates 5 upon the rear portions of which is suitably journaled a transverse horizontal drive shaft 6. The drive shaft 6 extends from one frame plate 5 to the other and is formed between these frame plates with a plurality of cranks 7 arranged in suitably staggered relation.

40 The shaft 6 may be driven by a suitable motor 8 disposed and suitably mounted beside the frame and having its power shaft operatively connected to the adjacent end of the drive shaft 6 as by means of spur gears indicated generally at 9. As shown, the cranks 7 are arranged in staggered relation upon the shaft 6.

45 Suitably journaled in the frame plates 5 near the forward ends of the latter and in a plane below the drive shaft 6 is a horizontal transverse driven shaft 10 adapted to be continuously rotated in accordance with the present invention by novel operative connection with the drive shaft 6, power being

taken from the shaft 10 in any suitable manner such as through the use of a pulley 11 fixed upon one end of the shaft 10 as shown clearly in the several views.

Pivoted for vertical rocking movement above the shaft 10 are a plurality of levers 12 which are arranged in spaced side by side relation between the frame plates 5 and correspond in number to the number of cranks 7 provided on the drive shaft 6, each lever 12 being aligned with one of the cranks 7 as shown clearly in Figure 2. The levers 12 are pivoted between their ends preferably upon a transverse horizontal hanger rod 13 whose ends are secured in the frame plates 5, and tilting movement of the levers 12 in one direction is limited by means of a transverse horizontal stop rod 14 supported by the frame plates 5 and disposed in the path of and below the rear ends of the levers 12 as shown clearly in Figure 4. This stop rod 14 is adjustable vertically for varying the tilting movement of the levers 12, and for this purpose the frame plates 5 are preferably provided with vertical series of transversely aligned pairs of apertures 15 adapted for selective reception of the ends of the stop rod 14, it being understood that the ends of the rods 14 are engaged in horizontally aligned ones of the apertures 15 in all adjusted positions.

50 A plurality of ratchet wheels 16 are fixed upon the shaft 10 between the frame plates 5 so that one ratchet wheel is disposed directly below each lever 12, and carried by the forward end of each lever 12 is a pawl 17 operatively disposed to engage and operate the adjacent ratchet wheel 16 upon each downward movement of the said lever 12. As shown, the pawls 17 are pivoted to the forward ends of the levers 12 so as to depend adjacent the forward sides of the ratchet wheels 16, and these pawls are preferably spring pressed into engagement with the ratchet wheels by leaf springs 18 or the like. It is thus apparent that upon rocking 55 the levers 12 the pawls 17 will act to turn the ratchet wheels 16 and consequently cause rotation of shaft 10, continuous rotation of the shaft 10 being effected by actuating the levers 12 so that certain of the pawls are returning for a new actuation of the associated ratchet wheels while others of the pawls are being moved downwardly and act-

ing to turn the other associated ratchet wheels. Obviously, the vertical adjustment of the rod 14 will result in varying the strokes of the levers 12 so as to thereby correspondingly vary the degree of movement imparted to each ratchet wheel 16 upon the effective or operative stroke of the associated pawl 17.

In order to effect the rocking of the levers 12, a heavy wheel 19 is disposed to roll on each lever 12 longitudinally of the latter and in a path backward and forward to opposite sides of the pivot of the lever. In order to guide the wheels 19 during their rolling movement and to effectively prevent their displacement laterally off of the levers 12, the latter are provided with suitable side guide rails 20 or the like between which the wheels 19 are disposed. With this arrangement the wheels roll directly upon the levers and are entirely supported by the same at all times so that a fixed supporting bed for the wheels independent of the levers is rendered unnecessary.

25 To effect the rolling movement of the wheels 19, each of said wheels is connected with the longitudinally aligned crank 7 of the shaft 6 by means of a pitman 21 having one end pivoted to an arm 22 projecting upwardly from the associated wheel 19 and having its other end journaled on the wrist pin of the associated crank 7. The pitmen 21 are of similar length, and by reason of the fact that the cranks 7 are in staggered relation, the wheels 19 will be moved so that certain of the same are moving forwardly for effecting the operative stroke of certain of the pawls 17 while others of the wheels 19 are moved rearwardly for effecting the return stroke of the remaining pawls. In the construction shown one pawl 17 will be completing its operative stroke or downward movement when another pawl has completed approximately its operative stroke, 45 and a third pawl will be just beginning its operative stroke.

The fourth pawl will then have just begun its return movement, while a fifth one will be at approximately the halfway position of its return stroke, and the last or sixth pawl will be just completing its return stroke, preparatory to beginning an operative movement. In this way a continuous rotation of shaft 10 is effected in a smooth even manner. Furthermore, the weight of the wheels 19 is utilized to effect turning of the shaft 10 rather than the direct force applied to the pitmen 21. This actuation of the shaft 10 is accomplished by means involving a minimum amount of friction, and as the shaft 10 will rotate at a slower speed than shaft 6, a leverage is had so that a comparatively great load may be imposed upon shaft 10 even though the motor 8 is of a comparatively small size and of low power.

In operation, the motor 8 is placed into operation so as to cause continuous turning of the shaft 6 and thereby effect rolling of the wheels 19 back and forth upon the levers 12. As the wheels 19 roll forwardly past the pivots of the levers 12, the latter will be rocked so as to cause downward movement of the attached pawls 17 and thereby effect rotation of shaft 10. As certain of the wheels 19 are moving forwardly, others will be moving rearwardly so that one or more pawls are active at all times in turning shaft 10.

From the foregoing description it is believed that the construction and operation so as well as the advantages of the present invention will be readily understood and appreciated by those skilled in the art.

Minor changes may be made without departing from the spirit and scope of the invention as claimed.

What we claim as new is:—

1. In a power transmission mechanism, a rotary drive shaft, a rotary driven shaft, a ratchet wheel secured on the driven shaft, a lever pivoted between its ends and having a pawl on one end operatively engaged with the ratchet wheel, a weighted wheel disposed for rolling movement on and longitudinally of said lever, and an operative connection between the wheel and the drive shaft for causing rolling movement of the wheel back and forth on the lever to opposite sides of the pivot of the latter.

2. A structure as specified in claim 1, wherein means is provided for adjustably limiting swinging movement of the lever for regulating the length of stroke of the pawl.

3. A structure as specified in claim 1, wherein said lever is provided with side guide rails between which the wheel is disposed to roll.

4. A structure as specified in claim 1, wherein the operative connection between the wheel and the drive shaft embodies a crank on the drive shaft, an arm rigid with and projecting upwardly from the wheel, and a pitman operatively connecting the arm with said crank.

5. A power transmission mechanism including a transverse horizontal drive shaft having a plurality of cranks arranged in staggered relation, a plurality of vertically swinging levers pivoted between their ends for independent rocking movement, a transverse horizontal driven shaft having ratchet wheels fixed thereon, a pawl carried by one end of each lever and operatively associated with one of said ratchet wheels, means associated with the other ends of the levers for limiting tilting movement of the levers in one direction during the inoperative movements of the pawls, a plurality of weighted wheels, each mounted for rolling movement

longitudinally of one of the levers, and pitmen connections between the wheels and the cranks of said drive shaft, whereby the pawls are actuated in sequence for causing continuous rotation of the driven shaft.

6. In a power transmission mechanism, a rotary drive shaft, a rotary driven shaft, a plurality of levers pivoted between their ends for vertical rocking movement independent of each other, a heavy wheel mounted to roll longitudinally upon each of said levers in a path to opposite sides of its pivot, means operatively connecting the wheels to the drive shaft for rolling the same back and forth in said path, and means operatively connecting the levers with the driven shaft for causing continuous rotation of the latter upon actuation of said wheels.
7. A power transmission mechanism comprising a frame having a pair of vertical side plates, a transverse horizontal drive shaft journaled on said side plates, a transverse horizontal driven shaft journaled in the side plates at a point below the drive shaft and forwardly of the latter, a plurality of vertically swinging levers pivoted between their ends in spaced side by side relation between the side plates and above the driven shaft, depending pawls upon the for-

ward ends of said levers operatively disposed forwardly of the driven shaft, ratchet wheels upon the driven shaft respectively engaged by said pawls, said side plates being provided with vertical series of transversely aligned openings, a stop rod selectively engageable in desired ones of said pairs of openings within the path of and below the rear ends of said levers for limiting the rocking movement of the latter, heavy wheels mounted to roll longitudinally on the levers past the pivots of the latter, and means operatively connecting the wheels with the drive shaft whereby the wheels are respectively positioned at different points of their path of travel at all times during the operation of the mechanism.

8. In a power transmission mechanism, a lever pivoted between its ends for vertical rocking movement and having side guide rails, a heavy wheel mounted for rolling movement on and entirely supported by said lever between said guide rails, means to roll said wheel back and forth past the pivot of the lever, and means to transmit movement from the lever to a driven element.

In testimony whereof we affix our signatures.

ARMOND D. HUDSON.
EDWARD L. SMITH.
